(57) **CLAIM**

The ornamental design for a breast shield connector for breast pump, as shown and described.

DESCRIPTION

FIG. 1 is a right, front perspective view of a breast shield connector for breast pump of the present invention; FIG. 2 is a left, rear perspective view of the breast shield connector for breast pump illustrated in FIG. 1; FIG. 3 is a front elevational view of the breast shield connector for breast pump illustrated in FIG. 1; FIG. 4 is a right side elevational view of the breast shield connector for breast pump illustrated in FIG. 1, the left side elevational view being a mirror image thereof; FIG. 5 is a rear elevational view of the breast shield connector for breast pump illustrated in FIG. 1; and, FIG. 6 is a top view of the breast shield connector for breast pump illustrated in FIG. 1. The broken lines in the drawings illustrate portions of the breast shield connector for breast pump that form no part of the claimed design.
